UNITED STATES PATENT OFFICE.

JAMES JAHSON WISHARD, OF SACRAMENTO, CALIFORNIA.

DITCHING-MACHINE.

SPECIFICATION forming part of Letters Patent No. 473,279, dated April 19, 1892.
Application filed September 2, 1891. Serial No. 404,519. (No model.)

To all whom it may concern:

Be it known that I, JAMES JAHSON WISHARD, of Sacramento, in the county of Sacramento and State of California, have invented 55
5 a new and Improved Ditching-Machine, of which the following is a full, clear, and exact description.

The object of the invention is to provide a new and improved ditching-machine which 10 is simple and durable in construction, very effective in operation, and in which the ground is taken up to the full width of the machine and deposited at one side of the latter to any desired distance.

15 The invention consists of certain parts and details and combinations of the same, as will be hereinafter fully described, and then pointed out in the claims.

Reference is to be had to the accompanying 20 drawings, forming a part of this specification, in which similar letters of reference indicate corresponding parts in all the figures.

Figure 1 is a plan view of the improvement with parts broken out. Fig. 2 is a side elevation 25 of the same. Fig. 3 is an end elevation of the same. Fig. 4 is a transverse section of the same on the line $x-x$ of Figs. 1 and 2. Fig. 5 is a longitudinal section of the same on the line $y-y$ of Fig. 1. Fig. 6 is an enlarged plan 30 view of a mechanism for winding the drum, and Fig. 7 is an end elevation of the plow.

The improved ditching-machine is provided with a suitably-constructed frame A, connected at its front end by a fifth-wheel B' with 35 the axle B², carrying the front wheels B. The rear end of the frame A is supported on the rear axle C', carrying the hind wheels C. Between the front and hind wheels B and C and near the former is arranged a plow D, provided with two parallel sides D' and an inclined bottom D², sloping rearward and upward, as is plainly illustrated in Fig. 5. The sides D' of the plow D are pivotally connected by links D³ with arms D⁴, secured on the frame 40 A and projecting downward from the same. In order to prevent sidewise motion of the plow D, bars D⁵ project downward from the frame A and engage the outside of the sides D'. Each of the sides D' of the plow D is 45 provided with a front post D⁶ and a rear post D⁷, of which the two front posts D⁶ are con-

nected with chains E, while the rear posts D⁷ are connected with chains E'. The chains E and E' extend upwardly and pass over pulleys E² and E³, respectively, mounted on the frame A, and then the said chains pass over pulleys E⁴ and E⁵, mounted to turn loosely on a transversely-extending shaft E⁶, held in brackets A', extending upward from the main frame A. The chains E extend rearwardly 60 from their pulleys E⁴ and wind on drums F, both secured on a transversely-extending shaft F', mounted to turn in suitable bearings formed on standards A², erected on the frame A near the rear end of the same. The 65 shaft F' carries a ratchet-wheel F², adapted to be engaged by a pawl F³, pivoted on a lever F⁴, fulcrumed loosely on the said shaft F', and adapted to be actuated by the operator standing on a platform A³, erected on the rear 70 of the frame A.

In order to prevent unwinding of the chains on the drums F, the shaft F' carries a ratchet-wheel F⁵, engaged by a pawl F⁶, pivoted on one of the standards A². (See Fig. 6.) The 75 other two chains E' extend rearwardly from the pulleys E⁵ and wind on drums G, both secured on a shaft G', mounted to turn in suitable bearings on standards A², previously mentioned. On one outer end of the shaft G' is 80 secured a hand-wheel G², under the control of the operator standing on the platform A³.

In order to lock the shaft G' in position, a ratchet-wheel G³ is secured on the said shaft and engaged by a pawl G⁴, pivoted on one of 85 the standards A². (See Figs. 1 and 3.) By the operator turning the shaft F so as to wind up or unwind the chains E the front part of the plow D can be raised or lowered, as desired. By turning the shaft G' so as to wind up or unwind the chains E' the rear part of the plow D can be raised or lowered.

On the front posts D⁶ are coiled springs H, and similar springs H' are coiled on the rear posts D⁷. The lower ends of the springs H and H' rest on the upper edges of the sides D', while the upper ends of the said springs H and H' are engaged by transverse bars H² and H³, respectively, fitted to slide on the said posts D⁶ and D⁷. The transverse bars H² and H³ are provided at or near their middle with arms H⁴ and H⁵, fulcrumed on brackets A⁴, pro-

jecting from the main frame A. The arm H⁴ extends forward, while the other arm H⁵ extends rearward, as is plainly illustrated in Fig. 5. The free end of the arm H⁴ is connected with the end of a chain H⁶ and the arm H⁵ is connected with a chain H⁷, both extending upward, the chain H⁶ passing over a pulley H⁸, held on the main frame A. The chains H⁶ and H⁷ then pass over two pulleys H⁹, mounted to rotate loosely on the shaft E⁶, previously mentioned. The chains H⁶ and H⁷ extend rearward from the said pulleys H⁹ to wind on the two drums I and I', respectively, secured on the shafts I² and I³, respectively, arranged vertically and mounted to turn in suitable bearings in the cross-beam of the standards A² in the main frame A.

The shafts I² and I³ are provided with hand-wheels I⁴ and I⁵, respectively, under the control of the operator standing on the platform A³. The upper ends of the shafts I² and I³ carry ratchet-wheels I⁶ and O⁷, engaged by pawls I⁸ and I⁹, pivoted on the cross-beam of the standards A², as is plainly shown in Figs. 1 and 3. By the operator turning the shaft I² by means of the hand-wheel I⁴ a pull is exerted on the chain H⁶, so that the cross-bar H² is pressed downward, thus exerting pressure on the spring H, and thereby forcing the front end of the plow downward in firm contact with the ground to be taken up. A similar pressure may be exerted against the rear of the plow D by the operator turning the shaft I³ so as to wind up the chain I⁷ and its drum I'. It will be seen that by this arrangement the plow D is yieldingly mounted so as to readily pass over any serious obstructions in the ditch-bed.

The rear upper end of the bottom D² of the plow D discharges onto an endless carrier-belt J, passing over the rollers J¹ and J², secured on shafts J³ and J⁴, of which the former is journaled below the bottom D² in the sides D' of the plow D. The shaft J⁴ is journaled in the belt-frame J⁵, secured at its upper end to the frame A and pivotally connected at its lower end by links J⁶ with the shaft J', previously mentioned. The links J⁶ permit of raising and lowering the plow D without changing the position of the carrier-belt J relative to the discharge end of the said plow D. The upper end of the carrier-belt J discharges onto a second carrier-belt K, arranged transversely and passing over rollers K' and K², journaled in a transversely extending frame K³, secured on the main frame A. The roller K² is located to one side of the main frame A, as is plainly shown in Fig. 4, and the belt K discharges over this roller K² onto the second transverse carrier-belt L, intended to carry the material to one side of the machine any desired distance. The endless belts K, J, and L are actuated simultaneously from the rear axle C' when the machine is moved forward.

In order to impart a traveling motion to the inclined belt J, the shaft J⁴ is provided on one

end with a sprocket-wheel J⁶, over which passes a sprocket-chain N, extending rearwardly and downwardly and passing with its lower part over an idler N', supported from the main frame A. The rear lower part of the sprocket-chain N passes over a sprocket-wheel N², secured on a transverse shaft N³, mounted to turn in suitable bearings on the rear part of the main frame A.

On the shaft N³ is secured a pinion N⁴ in mesh with a gear-wheel N⁵, mounted to rotate loosely on the axle C', carrying the hind wheel C. On the hub of the gear-wheel N⁵ are formed clutch-teeth adapted to be engaged by a clutch N⁶, held to slide on and to turn with the said axle C'. The clutch N⁶ is engaged with the lower end of a shifting lever N⁷, pivoted on the main frame A and extending through the platform A³, so as to be within convenient reach of the operator standing on the said platform A³. When the lever N⁷ is shifted so as to engage the clutch N⁶ with the clutch-teeth on the gear-wheel N⁵, then the latter rotates with the shaft C' when the machine is dragged forward. The gear-wheel N⁵ imparts a rotary motion to the pinion N⁴, so that the shaft N³ is rotated and the rotary motion of the latter is transmitted by the sprocket-wheel N² and the sprocket-chain N to the sprocket-wheel J⁶, whereby the shaft J⁴ is rotated and rotary motion is imparted to the carrier-belt J in the direction of the arrow a'.

On the shaft N³ is secured a bevel-gear wheel O, meshing into a bevel gear-wheel O', secured on a longitudinally-extending shaft O², mounted to turn in suitable bearings in the main frame A and carrying on its inner end a sprocket-wheel O³, over which passes a sprocket-chain O⁴, also passing over a sprocket-wheel O⁵, secured on the shaft K⁴ of the roller K'. Thus when the shaft N³ is rotated, as previously described, the gear-wheel O imparts a rotary motion to the gear-wheel O', thus rotating the shaft O², which by the sprocket-wheel O³, the sprocket-chain O⁴, and the sprocket-wheel O⁵ imparts a rotary motion to the shaft K⁴, so that the carrier-belt K is caused to travel in the direction of the arrow b'. On the inner end of the shaft O² is also secured a sprocket-wheel P, over which passes a sprocket-chain P', extending transversely and passing over a sprocket-wheel P², secured on the shaft L', carrying the roller L², over which the carrier-belt L passes. The latter also passes over the inner roller L³, journaled in a frame L⁴, which also supports the shaft L'. When the machine is dragged forward, the rotary motion of the shaft O² causes the sprocket-wheel P to rotate, so as to impart motion to the sprocket-chain P', which by passing over the sprocket-wheel P² rotates the shaft L', thus imparting a traveling motion to the carrier-belt L in the direction of the arrow c'.

The frame L⁴, supporting the carrier-belt L, is provided near its inner end with longitudi-

nally-extending trunnions L^5 , mounted in bearings Q , held adjustably in transversely-extending guideways Q' , supported from brackets Q'' , secured to the under side of the main frame A . The frame L^4 is thus pivoted on its inner end, the outer free end being connected with the chains R and R' , extending upwardly and inwardly and adapted to be wound on drums R^2 , secured on a longitudinally-extending shaft R^3 , mounted to turn in suitable bearings in one of the standards A^2 and in a bracket A^5 , erected on the main frame A .

On the rear end of the shaft R^3 is secured a hand-wheel R^4 within convenient reach of the operator standing on the platform A^8 . A ratchet-wheel R^5 is secured on the shaft R^3 and is adapted to be engaged by a pawl R^6 to prevent a rotation of the shaft R^3 and a consequent unwinding of the chains R and R' , and thus holding the free end of the frame L^4 in the proper position.

When it is desired to shift the carrier-belt L farther to one side of the machine, the operator moves the bearings Q on the guideways Q' , so that the frame L^4 slides outward to one side of the machine, carrying the carrier-belt L along. At the same time the operator turns the shaft R^3 so as to let out the chains R and R' to compensate for the outward movement of the carrier-belt frame L^4 . The latter can be raised or lowered at its free end by winding up or unwinding the chains R and R' on the drums R^2 . In case the frame L^4 , with the carrier-belt L , is moved outward, the chain P' has to be lengthened by adding the necessary number of links. Instead of doing this, however, the chain P' may be entirely disconnected from the sprocket-wheel P and passed over another sprocket-pulley, also driven from the shaft O^2 . The latter is for this purpose provided with a sprocket-wheel S , over which passes a sprocket-chain S' , extending transversely and passing over a sprocket-wheel S^2 , secured on a shaft S^3 , mounted to turn in suitable bearings on that side of the main frame A on which the carrier-frame is extended.

On the shaft S^3 is secured a sprocket-wheel S' , over which the chain P' is passed. When the machine is moved forward, the shaft S^3 is rotated from the shaft O^2 , so that a traveling motion is imparted to the sprocket-chain P' , and by the latter movement is imparted to the carrier-belt L in the manner previously described.

In order to clean or scrape off the plow D , a scraper T is provided, which extends transversely over the bottom D^2 of the plow between the sides D' . The scraper T is rigidly secured to an upwardly-extending arm T' , pivotally connected with a lever T^2 , fulcrumed loosely on the shaft E^6 , previously mentioned. The free end of the lever T^2 is guided vertically in guideways T^3 , erected on the front end of the frame A at the side of the driver's seat A^6 , so that the said lever T^2 is within convenient reach of the driver, who by press-

ing down the said lever engages the scraper T with the inclined bottom D^2 of the plow D . As the scraper T is slightly curved, as is plainly shown in Fig. 5, the said scraper moves forward, thus scraping off any dirt adhering to the bottom or sides of the plow.

In order to prevent the front wheels B from sinking too deep into the loose ground, two V -shaped plows U are mounted in front of the said wheels, so as to make a furrow to permit the said wheels to travel on hard ground. The plows U are secured on the front end of a frame U' , pivoted at U^2 to the under side of the axle B^2 . The free end of the frame U' is also connected by a rope or chain U^3 with one arm of a bell-crank lever U^4 , pivoted on the driver's seat A^6 and under the control of the driver seated on the said seat A^6 . The lever U^4 is also under the control of the operator standing on the platform A^8 . For this purpose the said lever is connected with a rope or chain U^5 , extending rearwardly and adapted to be fastened at its rear end on a cleat or pin U^6 .

The operation is as follows: The machine is drawn over the ground to be ditched in a suitable manner, the point of the plow D passing into the ground, so that the latter is plowed up, and passes over the inclined bottom of the plow onto the lower end of the traveling or carrier-belt J , which elevates the earth and finally discharges the same onto the transverse carrier-belt K . The latter discharges at the rear on one side of the machine onto the carrier-belt L , which carries the earth to a suitable distance to one side of the machine to finally discharge the same over the roller L^2 . It will be seen that the carrier-belt L can be moved to one side of the machine to a considerable distance, as the rear end of the belt K will still discharge onto the belt L in case the carrier-belt frame L^4 is moved into an extreme outer position. When the operator desires to press the point of the plow farther into the ground, he turns the hand-wheel I^4 so as to revolve the shaft I^2 to wind up the chain II^6 on the drum I^1 . The chain II^6 now pulls on the arm II^4 , which latter presses on the bar II^3 , thus compressing the spring II , and thereby exerting a pressure onto the front end of the plow, so that the latter swings downward, the operator at the same time giving considerable slack to the chains E by unwinding them from the drums F on the shaft F^2 . The plow may be raised entirely out of the ground whenever desired by the operator working simultaneously the lever F^4 and the hand-wheel G^2 , so as to wind up the chains E and E' . When the plow is raised, the lower end of the carrier-belt J is also elevated so as to be off the ground as the shaft J' of the said belt is mounted to turn in the sides D' of the plow. The operator can stop the belts J , K , and L from traveling at any time he desires by operating the lever N^7 , so as to throw the clutch N^6 out of mesh with the clutch-teeth on the gear-wheel N^5 . The op-

erator can stop the belts J , K , and L from traveling at any time he desires by operating the lever N^7 , so as to throw the clutch N^6 out of mesh with the clutch-teeth on the gear-wheel N^5 . The op-

erator can clean the plow by the scraper T at any time whenever found necessary. Thus it will be seen that the several working parts of the machine are under full control of the operator.

5 Having thus fully described my invention, I claim as new and desire to secure by Letters Patent—

1. The combination, with the main frame, 10 the plow, and the longitudinally-inclined elevator extending upward and rearward therefrom, of two parallel drums or rollers extending longitudinally along opposite sides of the frame in rear of said elevator, an endless belt 15 mounted on said drums or rollers and extending transversely across the main frame, and a second endless carrier having a supporting-frame pivotally supported at its inner end beneath the inner end of said endless belt, extending outward from the opposite side of the 20 main frame and provided with means for adjusting its delivery end up or down, substantially as set forth.

2. The combination, with the main frame, 25 the plow, and the elevator, and the transverse carrier-belt at the upper end thereof, of depending brackets Q², provided at their lower ends with transversely-extending guideways Q', bearings Q, adjustable in said guideways, 30 a frame L, mounted at its inner end on said bearings and provided with means for adjusting its outer end, and an endless carrier mounted on the frame L, substantially as set forth.

3. The combination, with the main frame and its plow having an inclined bottom, of the roller mounted under said bottom, links J⁶, projecting rearward from the ends of the lower roller, the elevator-frame pivotally connected 40 at its lower end with the rear ends of said links and extending upwardly and rearwardly therefrom and having a roller at its upper end, and the endless elevator extending around said rollers, substantially as set forth.

4. In a ditching-machine, the combination, 45 with a plow provided with an inclined bottom and parallel sides, of posts formed on the sides of the said plow, cushioning-springs carried by said posts, and chains connected with the 50 said posts to support the said plow, substantially as shown and described.

5. In a ditching-machine, the combination, 55 with a plow provided with an inclined bottom and parallel sides, of front and rear posts formed on the sides of the said plow, chains connected with the said posts to support the said plow, and means, substantially as described, for raising or lowering the said chains independently of each other, substantially as shown and described.

6. In a ditching-machine, the combination, 60 with a plow supported on chains adapted to be raised or lowered, of springs pressing on the said plow, cross-bars pressing on the said 65 springs and provided with pivoted arms, and chains connected with the said pivoted arms

to increase or diminish the pressure on the said springs, substantially as shown and described.

7. In a ditching-machine, the combination, 70 with a plow supported on chains adapted to be raised or lowered, of springs pressing on the said plow, cross-bars pressing on the said springs and provided with pivoted arms, chains connected with the said pivoted arms 75 to increase or diminish the pressure on the said springs, and mechanism, substantially as described, for exerting a pull on the said chains connected with the arms independently of each other, substantially as shown 80 and described.

8. In a ditching-machine, the combination, 85 with a frame mounted on front and hind wheels, of triangular plows arranged in front of the said front wheels to form a furrow for the latter, substantially as shown and described.

9. In a ditching-machine, the combination, 90 with a frame mounted on front and hind wheels, of triangular plows arranged in front of the said front wheels to form a furrow for 95 the latter, a pivoted frame supporting the said plows, and means, substantially as described, for raising and lowering the said plows, as set forth.

10. In a ditching-machine, the combination, 100 with the main frame provided with rigid guideways, of bearings held adjustably in the said guideways, trunnions engaging the said bearings, a carrier-belt frame on which the said trunnions are secured, a carrier-belt mounted to turn in the said belt-frame, and means, substantially as described, for raising and lowering the free end of the said carrier-belt frame, 105 substantially as shown and described.

11. In a ditching-machine, the combination, 110 with a main frame mounted on wheels, of a plow held on chains supported on the said main frame, links connected with the sides of the said plow and connected with the brackets on the said main frame, and means, substantially as described, for raising or lowering either end of the said plow, substantially as shown and described.

12. In a ditching-machine, the combination, 115 with a plow provided with an inclined bottom and parallel sides, of posts formed on the sides of the said plow, chains connected with the said posts to support the said plow, means, substantially as described, for raising or lowering the said chains independently of each other, and fixed guide-arms engaging the sides of the said plow to prevent sidewise movement of the plow, substantially as shown and described.

13. In a ditching-machine, the combination, 120 with a plow having an inclined bottom, of a scraper arranged vertically and adapted to pass over the said inclined bottom to clean the plow, substantially as shown and described.

14. In a ditching-machine, the combination,

with a plow having an inclined bottom, of a scraper arranged vertically and adapted to pass over the said inclined bottom to clean the plow, and a lever adapted to be swung up and down and pivotally connected with the said scraper, substantially as shown and described.

15. In a ditching-machine, the combination, with a plow, of chains connected with said plow for raising, lowering, or tilting the said plow, winding-drums for actuating the said chains, and a transverse shaft carrying pulleys over which pass the said chains from the

said plow to the winding-drums, substantially as shown and described.

16. In a ditching-machine, the combination, with a plow provided on its sides with posts, of chains connected with the said posts and two independent winding-drums for winding up the chains independent of each other to raise or lower the plow or one end thereof, substantially as shown and described.

JAMES JAHSON WISHARD.
